UNITED STATES PATENT OFFICE.

ARTHUR NATHAN, OF CHARLOTTENBURG, GERMANY.

LOCKING DEVICE FOR CARRIAGE-DOORS.

No. 867,747.

Specification of Letters Patent.

Patented Oct. 8, 1907.

Application filed October 22, 1906. Serial No. 340,044.

To all whom it may concern:

Be it known that I, ARTHUR NATHAN, engineer, a citizen of Germany, and a subject of the King of Prussia and Emperor of Germany, residing at 87 Goethestrasse, 5 Charlottenburg, near Berlin, in the Kingdom of Prussia and Empire of Germany, have invented new and useful Improvements in Locking Devices for Carriage-Doors, of which the following is a specification.

The present invention refers to a locking device for 10 carriage-doors, particularly for doors of railway-carriages, on which the inside and the outside handles are arranged movable independently of each other. The important feature is that the inside handle is fitted with a catch or ratchet, which prevents the lock from 15 being unintentionally opened from the inside, whereas at the same time means are provided to secure a joint and guided motion of the two independently movable handles, when the inside handle is not caught by the ratchet or catch. Herein it will be of advantage to 20 employ as a catch for such locking purpose a straight lever pivotally arranged lateral to the knob of the inside handle which lever engages with a short arm, while locking the inside handle with a stop provided on the inside of the door. The outer end of this short arm 25 is suitably made in the shape of a hook, so that the lever while in locking position can catch beneath a correspondingly shaped projection provided on the inside of the door, whereby the inside handle is also secured against tensile strain.

30 In order to secure the moving of the second handle on the first one being moved, when the inside handle is not caught and when locks which are not self-closing are employed, a spring is arranged between and connected with both said handles.

35 In the accompanying drawings a mode of carrying out such an arrangement is exemplified, Figure 1 showing the profile of a carriage door with outside and inside handle partly in section, the lock itself being removed, and the inside handle being secured; Fig. 2 shows the 40 inside handle unlocked; Fig. 3 represents a side view of the inside handle with securing lever; Fig. 4 represents a plan of inside handle with securing lever; Fig. 5 represents a detail; Fig. 6 represents a side view and a plan of the part provided on the inside of the door 45 and serving as a stop and guide for the securing lever; and Fig. 7 represents a section through the stem and the parts connected thereto taken on line A—A in Fig. 1, in two different positions.

50 The inside handle 1, which has the crank-like shape customary in railway-carriages, has in handgrip or knob 2 a slot 3. In said slot 3 is arranged a spring 4, one end of which is attached to knob 2 and the other end secured to a double-armed lever 5. This double-armed lever 5 has its pivotal point 6 at the inside handle, and

the lower, shorter arm 7 of which has a hook-terminal, 55 as seen in Fig. 3, and to catch under projection 8, (Fig. 6), of the guide-rail 9.

The outside handle 10 is of the usual shape and is rigidly connected with the stem 11. Said stem 11 is of a round tapering shape at 12 beyond its usual square 60 part. On this tapering part a dog-sleeve 13 is keyed, the end 13' of which points toward the inside handle and is partly cut away to form stops. A second dog sleeve 14 (Fig. 5) is loosely arranged on said stem, the inner end 15 of which points towards sleeve 13, and is 65 cut away in a corresponding manner to form stops for engagement with stops on sleeve 13. This sleeve 14 is keyed to the angular bore 16 (Fig. 4) of the inside handle 1. The connection between the inside and outside handles is obtained by the stem 11 which extends through the bore 17 of sleeve 14 and bore 16 of handle 1, and has a nut 18 on its outwardly projecting end.

If a lock which is not self-closing is employed, it will be advantageous to slip a spring 19 on stem 11, one end 75 of which spring is secured at 20 to stem 11, and the other end being attached at 21 to sleeve 14.

The operation is as follows:—When the door is closed, the hooked arm 7 of the lever 5 will catch beneath the projection 8 of guide rail 9 and thereby prevent the inside handle 1 from being unintentionally pressed down. Notwithstanding this locking, however, the door can be 80 opened by turning the outside handle 10, as the stops 13' and 15 of the two sleeves have sufficient play, to allow the turning of the knob of the outside handle 85 around an angle of about 90°, as shown in Fig. 7. The edge 22 of the lug 13' will thereby recede from edge 23 of lug 15. In a corresponding manner the door can also be closed by turning the outside handle 10 while the inside handle is locked, whereby edge 22 of sleeve 13' 90 will again abut against edge 23 of sleeve 15. If on the contrary the door is to be opened from the inside, the knob 2 of the inside handle 1 is seized with the hand and the long arm of lever 5 on the side of said handle pressed into slot 3 against the tension of spring 4, whereby arm 7 is forced out and disengaged from projection 8, and the inside handle can now be turned downward in the usual manner, whereby arm 7 will glide along the curve of rail 9. During this turning of the inside handle 1, the outside handle 10 is turned also by stop 100 23 of sleeve 15 pressing against stop 22 of sleeve 13' and thereby turning the latter and the connected stem 11 with handle 10.

When the door is to be again closed by turning the outside handle, the inside handle is simultaneously 105 turned into locking position by the coöperation of edges 22 and 23 in opposite direction. If, however, the door is to be closed by raising the inside handle, the

- outside handle cannot be simultaneously moved by the coöperation of the two sleeves. If self-closing locks are used, particularly such as described in the British Patent No. 23239, 1905, the two handles are returned 5 into locking position automatically both in the manner as in the former instance. If, however, the arrangement is employed with one of the known locks which is not self closing, the moving of the outside handle on the door being closed by raising the inside handle would 10 only be effected by the friction between the screw-nut 18 and the inside handle 1, if spring 19 were not provided. When the inside handle is raised, said spring is put under tension, thereby tending to turn the outside handle. As soon as the inside handle reaches its locking 15 position, lever 5 under the action of the spring 4, will automatically slip into catching position, so that an unintentional touch of the inside handle inside the carriage, as by leaning the body against said handle or by jars or the like, cannot press down said handle.
- 20 The details of the device may be varied in manifold manner. The hook provided on lever 7 may be omitted and the lever 7 will then only press against stop 8. However, it is of advantage to employ such a hook, as a 25 loosening of the safety and a bending of the inside handle even under tensile strain is avoided. In place of the dog-sleeves with stops, any other suitable device may be employed for obtaining the same purpose.
- Corresponding safety-arrangements may also be fitted to the inside handle, even if the latter is of any other 30 construction or design, than the one described in the present specification.
- Having now described my invention what I claim and desire to secure by Letters-Patent of the United States is:—
- 35 1. In a locking device for doors of railway carriages with operating handles pivoted apart from each other,

with coengaging stops carried by the shafts of both handles and a catch arranged on the inside handle to engage a stop and for preventing the lock from being unintentionally opened from the inside, a spiral spring, 40 one end of said spring being connected with one of said handles, the other end being connected with the other handle.

2. In a locking device for doors of railway carriages the combination of operating handles pivoted apart from each other, coengaging stops connected with the shafts 45 of both handles, a lever pivotally connected with the inside handle, an engaging member for said lever on the inside of the door, a spiral spring wound around the shafts of both of the operating handles, one end of said 50 spring being connected with one of said shafts and the other end with the other shaft.

3. In a locking device for doors of railway carriages the combination of operating handles pivoted apart from each other, coengaging stops connected with the shafts 55 of both handles, a lever pivotally connected to the inside handle, a hook on the free end of said lever, a notch on the inside of the door, said hook engaging said notch for securing the inside handle, means connected with both handles and independent of said engaging 60 stops on said shafts for securing the joint guided motion of the operating handles when the inside handle is disengaged and the lock is closed by the turn of said inside handle.

4. In a locking device for doors of railway carriages 65 the combination of operating handles pivoted apart from each other, coengaging stops connected with the shafts of both handles, a straight lever pivotally connected with the inside handle, a hook on the free end of said lever, a notch on the inside of the door, said hook en- 70 gaging said notch for securing the inside handle, a spiral spring around the shafts of said handles, one end of said spring being connected with one of said operating handles and the other end with the other operating handle.

In testimony whereof I have hereunto set my hand in 75 presence of two subscribing witnesses.

ARTHUR NATYAN.
